(Cl. D29—20)

FIG. 3

FIG. 4

FIG. 1 is a front perspective view of an easel showing our new design;

FIG. 2 is a rear view in a reduced scale;

FIG. 3 is a front view of the easel shown in FIG. 1 as it appears with the longitudinal elastic band in a slightly raised position; and

FIG. 4 is a side view thereof, the side opposite being a mirror image thereof.

The fragmentary broken line showing of supporting structure in FIG. 4 is merely for illustrative purposes.

We claim:

The ornamental design for an easel, as shown and described.
